UNITED STATES PATENT OFFICE

SHOLTS H. BOYD, OF VENICE, CALIFORNIA

DOOR AND WINDOW FRAME CONSTRUCTION

Application filed May 16, 1930. Serial No. 452,993.

My invention relates to building construction, and particularly to the construction of frames for doors and windows in a building the walls of which have an exterior coating of 5 stucco or the like and an interior coating of plaster or the like.

In the usual construction, a window or door frame proper is mounted in a rough frame provided in the studding of the building and 10 then after the wall coatings are applied outside and inside architraves and trim are added to form stops for the interior and exterior wall coatings to give a finished appearance to the window or door opening, and to serve 15 as stops or retaining members for sash and doors, which necessarily are installed in the frames only after the walls are finished.

My invention contemplates using for the stiles and yoke of such an inner frame a member of novel cross-section in which longitudinal grooves serve as stops for the outside and inside wall coatings.

With my construction the addition of outside and inside architraves and trim is unnecessary. The elimination of such members not only saves considerable labor and materials, but also by reducing the visible wood-work results in a pleasing simplicity of design.

20 The grooved member may be provided with an integral flange positioned to abut a door in the door frame, or, in the case of a window frame, to function as a guide or keeper for a sash in the absence of the edge of an architrave usually overhung for that purpose. The provision of such an integral flange is further economy in construction.

An important advantage of my invention is that a frame having sash or a door already 25 hung therein may be mounted complete in the rough framing of a building before the wall coatings are applied, so that all the operations are finished at once. In fact, frames may be so completed at a central shop and delivered to the job.

These and other objects and advantages of my improvement will appear from the following specification, reference being made to the accompanying drawing wherein I have illustrated my specific embodiment.

In the drawing—

Fig. 1 is a cross-section of the member designed for a double-sash window frame;

Fig. 2 is a horizontal cross-section of a double-sash window jamb construction incorporating the member shown in Fig. 1, the sash being shown in plan; 55

Fig. 3 is a transverse vertical section of a double-sash window frame incorporated in a finished wall, the sashes being shown in elevation; and 60

Fig. 4 is a fragmentary horizontal section of a door jamb construction incorporated in a finished wall.

In the course of erecting a building the 65 openings for doors and windows are defined by rough frame members 10, usually two-by-four studding and horizontal pieces, as shown in Figs. 2, 3 and 4. The finished inner frames to be mounted therein are generally delivered 70 to the job already assembled. Such an inner frame for a double-sash window incorporating my invention may comprise two vertical stiles 11, a yoke 12, a sill 13, and a stool 14. Fig. 1 shows in cross section the preferred form of my improvement designed for 75 the stiles 11 and yoke 12 of such a frame. It is provided on one edge with a longitudinal groove 15 to receive the exterior wall coating 16, and on the opposite edge with a similar 80 longitudinal groove 17 to serve as a stop for the interior wall coating 18, and a longitudinal slot 19 on one face to seat a parting strip 20, which is preferably all metal.

A projecting longitudinal flange 21, preferably integral with the frame member used for stiles 11 and yoke 12, is provided to form, with parting strip 20, a longitudinal channel in which an upper sash 22 slides and a stop bead 23 is attached to the opposite edge 90 of the stile or yoke to form, with parting strip 20, a second channel for a lower sash 24. These features may be common to both the stile and the yoke. The stiles are provided with counterbalancing means connected to the two sash. In the drawing a well-known type is shown, comprising essentially a strap 25 attached to a sash and a housing 26 containing a spring-actuated mechanism for winding up the strap. 95

Rough blocking is used to mount the window frame within the rough framing of the building. In Fig. 3 a block 27 so employed is shown between yoke 12 and the rough framing 10, and at the bottom a wedge 28 is shown between the sill 13 and the rough framing 10. In Fig. 2 a shim 29 and block 29a between stile 11 and the rough framing 10 bridges the space required for housing 26 which projects from the stile.

In the usual stucco structure, building paper 30 is first applied to the outside of the wall and then wire mesh or metal lath 31 is secured by nails 32 and washers 33. Where my invention is used the edges of the metal lath are secured in the groove 15 of the stile and yoke of the window frame, and the stucco is finished off at the groove as shown.

On the interior wall preferably a strip of metal lath 31a is applied in the same manner spanning from the interior wood lath 34 to groove 17, to serve as a bond or reinforcement for the interior plaster which is finished off at groove 17 in the manner shown. An apron 35 may be used as a stop for the plaster under stool 14 in the usual manner.

Fig. 4 shows my invention applied to the construction of a door frame. The door jamb 36 and the head of the door frame (not shown) have grooves 15 and 17 identical with the grooves in the window frame described above and serving the same purpose. A shoulder 37 which may be integral with the jamb or head projects to abut a door 38 mounted to the jamb by hinges 39 in the usual manner.

Obviously either the interior groove or the exterior groove may be omitted or neglected if it is desired to use architraves or trim as a stop for one of the wall coatings after the manner of the usual construction.

In describing the preferred form of my invention I reserve the right to all modifications in structure or form that properly come within the scope of the claims appended hereto.

Having thus described my invention, I claim:

1. A door and window frame construction comprising, in combination: a frame member; a plaster wall coating; the frame member having an outer surface extending substantially parallel with and normally back of the outer surface of the plaster coating; the said outer surface of the frame member having a groove therein extending inwardly at substantially right angles to the plane of the plaster coating, the terminal edge of the plaster coating being extended into said groove.

2. A door and window frame construction comprising, in combination: a wooden frame member; a plaster wall coating; the frame member having an outer surface extending substantially parallel with and normally

back of the outer surface of the plaster coating; the said outer surface of the frame member having a groove therein extending inwardly at substantially right angles to the plane of the plaster coating, the terminal edge of the plaster coating being extended into said groove.

3. A door and window frame construction comprising, in combination with a plastered wall having an opening therein; a rough frame member; an outer finishing frame member secured to the rough frame member, the finishing frame member having an edge extending in a plane substantially parallel with and back of the normal outer plaster surfacing, said frame member also having a longitudinal groove in said edge extending inwardly therefrom at substantially right angles to the plane of the wall; and a plaster coating on said wall, the terminal edge of which coating is extended into said groove.

4. A door and window frame construction comprising, in combination with a plastered wall having an opening therein: a rough frame member; an outer wooden finishing frame member secured to the rough frame member, the finishing frame member having an edge extending in a plane substantially parallel with and back of the normal outer plaster surfacing, said frame member also having a longitudinal groove in said edge extending inwardly therefrom at substantially right angles to the plane of the wall; and a plaster coating on said wall, the terminal edge of which coating is extended into said groove.

5. A door and window frame construction comprising, in combination with a wall having a surface adapted to receive a plaster coating: of a frame member secured to the end of said wall, said frame member having an edge extending in the direction of said wall surface and in which edge there is a longitudinal groove extending at substantially right angles to said wall surface; a metal lathing secured over said wall surface and having its terminal edge extended into said groove; and a plaster coating applied to said surface over said lathing and having its terminal edge rounded and extended into said groove around said terminal edge of the lathing therein.

6. A door and window frame construction comprising, in combination with a wall having a surface adapted to receive a plaster coating: of a wooden frame member secured to the end of said wall, said frame member having an edge extending in the direction of said wall surface and in which edge there is a longitudinal groove extending at substantially right angles to said wall surface; a metal lathing secured over said wall surface and having its terminal edge extended into said groove; and a plaster coating applied to said surface over said lathing and having its ter-

minal edge rounded and extended into said groove around said terminal edge of the lathing therein.

7. A door and window frame construction comprising, in combination with a wall having a surface adapted to receive a plaster coating: of a rough frame member secured to the end of said wall; an outer finishing frame member secured to said rough frame member,

10 the finishing frame member having an outer surface extending in the direction of said wall surface and in a plane back of what will normally be the outer surface of the plaster coating, said frame member having a longitudinal

15 groove in said outer surface extending at substantially right angles to the said wall surface; a metal lathing extending over said wall surface and having its terminal edge extended into said groove; means for securing said

20 lathing in place; and a plaster coating applied to said wall surface over said lathing and having its terminal edge rounded and extended into said groove around said terminal edge of the lathing therein.

25 8. A door and window frame construction comprising, in combination with a wall having a surface adapted to receive a plaster coating: of a rough frame member secured to the end of said wall; an outer wood finishing frame member secured to said rough frame member, the finishing frame member having an outer surface extending in the direction of

30 said wall surface and in a plane back of what will normally be the outer surface of the plaster coating, said frame member having a lon-

35 gitudinal groove in said outer surface extending at substantially right angles to the said wall surface; a metal lathing extending over said wall surface and having its terminal edge

40 extended into said groove; means for securing said lathing in place; and a plaster coating applied to said wall surface over said lathing and having its terminal edge rounded and extended into said groove around said

45 terminal edge of the lathing therein.

9. A door and window frame construction comprising, in combination with a wall having a surface adapted to receive a plaster coating: of a rough frame member secured to the

50 end of said wall; an outer finishing frame member secured to said rough frame member, the finishing frame member having an outer surface extending in the direction of said wall surface and in a plane back of what will nor-

55 mally be the outer surface of the plaster coating, said frame member having a longitudinal groove in said outer surface extending at sub-

60 stantially right angles to the said wall surface; a metal lathing extending over said wall

65 surface and having its edge terminated at said groove; means for securing said lathing in place; and a plaster coating applied to said wall surface, over said lathing, and having its terminal edge rounded and extended into

10. A door and window frame construction comprising, in combination with a wall having a surface adapted to receive a plaster coating: of a frame member secured to the end of said wall, said frame member having an 70 edge extending in the direction of said wall surface and in which edge there is a longitudinal groove extending at substantially right angles to said wall surface; a metal lathing extended over said wall surface and having its edge terminated at said groove; means for securing said metal lathing in place; and a plaster coating applied to said wall surface, over said lathing, and having its terminal edge rounded and extended into 75 said groove.

11. A door and window frame construction comprising, in combination with a wall having a surface adapted to receive a plaster coating: of a wooden frame member secured to the end of said wall, said frame member having an edge extending in the direction of said wall surface and in which edge there is a longitudinal groove extending at substantially right angles to said wall surface; a metal 85 lathing extended over said wall surface and having its edge terminated at said groove; means for securing said metal lathing in place; and a plaster coating applied to said wall surface, over said lathing, and having its terminal edge rounded and extended into 90 said groove.

In witness that I claim the foregoing I have hereunto subscribed my name this 5th day of May, 1930.
